UNITED STATES PATENT OFFICE.

BELLE V. HERMAN, OF CENTRALIA, WASHINGTON.

PIE AND CAKE CARRIER.

1,249,082.

Specification of Letters Patent.

Patented Dec. 4, 1917.

Application filed May 18, 1917. Serial No. 169,485.

To all whom it may concern:

Be it known that I, BELLE V. HERMAN, a citizen of the United States, residing at Centralia, in the county of Lewis and State 5 of Washington, have invented certain new and useful Improvements in Pie and Cake Carriers; and I do hereby declare the following to be a full, clear, and exact description of the invention, such as will enable 10 others skilled in the art to which it appertains to make and use the same.

This invention relates to improvements in article carriers of the type designed to carry cakes, pies, hot dishes, pans and the like, 15 and an object of the invention is the provision of a simple, durable and efficient device of this character.

Other objects will appear and be better understood from that embodiment of my 20 invention of which the following is a specification, reference being had to the accompanying drawing forming a part thereof, in which:

Figure 1 is a top plan view of the device, 25 with the clamping jaws in their innermost position,

Fig. 2 is a side elevation of the device,

Fig. 3 is a plan view of the supporting frame for the jaws, with the latter in their 30 outermost position, and

Fig. 4 is a detail sectional view, taken through the frame, and showing one of the clamping jaws and the operating member therefor.

Referring to the drawing in detail, the 35 numeral 1 designates a supporting frame which is formed by bending one end of a flat strip of metal into circular form, the other end of the strip being extended radially and terminally bent to provide a handle 3. While the frame 1 is shown of circular shape, it is to be understood that the same can be square or any other shape. Pivots associated with the frame 1 and

40 depending therefrom is a plurality of clamping jaws 4. Each of these jaws 4 is formed of a single length of wire bent into substantially U form and the upper ends of the sides of each jaw 4 are passed through 45 a pair of openings in the frame 1 and bent to provide the loops or eyes 5, whereby to serve as attaching means for holding the jaws 4 on the frame 1. The jaws 4 are adapted to have outward swinging move- 50

ment on the frame 1 and each jaw is of 55 arcuate shape, as shown more particularly

in Fig. 4, and has the lower ends thereof offset inwardly to provide a flange 6.

Positioned above the frame 1 is a jaw operating member which is formed of a pair 60 of intersecting wires 7 and 8. These wires 7 and 8 extend through intersecting recesses formed in a plate 9, which are positioned in concentric relation with the frame 1. A second plate 10 is superposed on the plate 9, and a fastening element 11 extends through the plates 9 and 10 and through the points of intersection between the wires 7 and 8, the said wires 7 and 8 being flattened at their point of intersection, for this purpose. The 70 wires 7 and 8 have their respective ends bent and extended downwardly beyond the frame 1, as shown at 12, and terminally bent to provide loops 13 that receive the respective jaws 4. The jaw operating member is adapted to have movement toward and away from the frame 1, and when moved in a direction away from the frame will result in the looped ends 13 effecting a lifting force on the jaws 4 so as to move the jaws outwardly 80 and upwardly, and when the movable member is returned to normal position the jaws 4 will likewise be returned to normal position. The jaw operating or movable member is provided with a manipulating handle 85

14 that is formed of a single length of wire having one end bent, as shown at 15, and terminally extended between the plates 9 and 10 and secured in place by the fastening element 11. The handle 14 is arranged in 90 intersecting relation with the handle 2, and is provided, at the point of intersection, with an eye 16, through which extends a pivot pin 17, the said pivot pin 17 pivotally connecting the handle 14 to the handle 2. 95

The free end of the handle 14 is disposed below the free end of the handle 2, and is bent to provide a hand grip 18 that is located below the hand grip 3 on the handle 2.

In use, the free end of the handle 14 is 100 moved downwardly, resulting in the jaw operating or movable member being raised and effecting an outward and upward movement of the jaws 4. The jaws 4 are then passed over the article to be carried, and the free end of the handle 14 is raised so as to move the jaws inwardly and engage the flanges 6 beneath the article. The article can then be lifted and carried any distance and released at any desired points.

It is evident that various changes might be resorted to in the form, construction and

arrangement of the several parts without departing from the spirit and scope of the invention as claimed.

Having thus described my invention what I claim as new, is:

- 5 1. In an article carrier, a frame, a plurality of arcuate shaped jaws pivotally mounted on the frame, and a jaw-operating member mounted for movement with respect to the frame and formed of a pair of intersecting wires having their ends provided with loops for receiving the respective jaws.
- 10 2. An article carrier, a frame, a handle formed integrally with and extending radially from the frame, a plurality of jaws pivotally mounted on the frame, and depending therefrom, a pair of intersecting elements located upon the frame and having operative connections with the jaws, and a
- 15 20 manipulating handle pivotally secured to

the handle of the frame, and intersecting elements to facilitate the operation of the jaws, as and for the purpose set forth.

3. An article carrier, a frame, a handle formed integrally with and radiating from said frame, a plurality of jaws pivotally secured to and depending from the frame, a jaw operating member mounted above said frame and operatively connected with the jaws, and means pivotally secured to the jaw operating member and to the handle of the frame for facilitating the opening and closing of the said jaws, as and for the purpose specified.

In testimony whereof I affix my signature in presence of two witnesses.

BELLE V. HERMAN.
